FIG. 1

FIG. 3

FIG. 1 is a perspective view of a comb showing my new design;

FIG. 2 is a top plan view thereof; and

FIG. 3 is an end elevational view taken from the right of FIG. 1.

The dominant features of my design reside in the full line disclosure, the broken lines indicate a transparent cap portion through which the spray nozzle portion is visible.

I claim:

The ornamental design for a comb, substantially as shown and described.
